LOCOMOTIVE STOKER

Nathan M. Lower, Pittsburgh, Pa., assignor to
 The Standard Stoker Company, Incorporated,
 a corporation of Delaware

Application June 12, 1929. Serial No. 370,298

1 Claim. (Cl. 110—101)

This invention relates to the improvement in stokers delivering coal from the tender to an opening in the backhead of a locomotive which comprises a conduit rigidly attached to the backhead, a conduit rigidly attached to the tender, and an intermediate conduit flexibly connecting the first two conduits; and relates particularly to the improvement in construction of the conduit attached to the backhead so that coal can be easily transferred through the three conduits by a screw conveyor having a minimum number of flexible joints.

Novel details of construction, which increase the efficiency of this type of stoker, will be apparent during the course of the following description taken in connection with the accompanying drawing, in which:

Fig. 1 is a vertical longitudinal sectional view of a locomotive and tender, and illustrates the improved stoker applied thereto.

Fig. 2 is a sectional view taken on line 2—2 of Fig. 1.

Fig. 3 is a sectional view taken on line 3—3 of Fig. 1.

Referring to Fig. 1, the numeral 1 designates the locomotive cab; 2, the locomotive cab deck; 3, the back wall or backhead of the firebox; 4, the locomotive frame; 5, the tender; and 6, the tender deck.

The stoker comprises three main units or conduits, namely; the backhead conduit or nozzle 32, the tender conduit or trough 26, and the inclined intermediate conduit 22. The conduit 32 is rigidly fixed to the backhead 3 by any desirable

and known means such as bolts 3a extending through the flange 3b which extends laterally of the conduit 32 beyond the marginal edges of the firing opening 29. The conduit 32 is in communication with the lower portion of the firing opening 29 which accommodates hand and stoker firing. It is preferable that the backhead conduit 32 be inclined and straight. By eliminating sharp turns or bends in this conduit the passage of coal through it is not obstructed. It is more particularly important that the bottom surface 7 of the backhead conduit 32 be inclined and straight, since this is the surface over which the fuel moves.

The trough 26 is provided with rollers 14, and is moved to its proper location beneath the tender deck 6 by rolling it rearward on the tracks 15 in the tender. The trough 26 is arranged horizontally, and is rigidly secured at its rear end to the under side of the tender deck 6 by means

ward end to the tracks 15 by means of a bracket 25. The trough 26 extends forward to a point substantially beneath the cab deck 2. The sealing angle 27, between the tender deck 6 and the trough 26, is secured to the tender deck by bolts 28, and prevents coal from spilling out over the sides 29 of the trough. A conveyor screw 18 moves the coal through the entire length of the trough 26. It is driven at its rear end in the usual and well known manner and need not be described.

Arranged in end to end relation with the backhead conduit 32 and the trough 26 is the intermediate conduit 22. The intermediate conduit 22 projects through the cab deck 2 and extends into the locomotive cab, and its lower end terminates beneath the cab deck. It comprises a rearward portion 30 and a forward portion 31 which are capable of telescopic movement in relation to each other. The rearward portion 30 is flexibly connected to the forward end of the trough 26 by the ball joint 8, and the forward portion 31 is flexibly connected to the backhead conduit 32 by the ball joint 9. This construction permits angular movement between the locomotive and tender as they negotiate curves. A conveyor screw 23 extends throughout the entire length of the intermediate conduit 22 and projects into the backhead conduit 32, and is arranged to transfer fuel through the intermediate conduit 22 and the backhead conduit 32 without substantially changing the path of the fuel. The inclined conveyor screw 23 is universally jointed to and driven by the horizontal conveyor screw 18.

The cover 37 is rigidly secured to the deck 90 and rests on the fixed conduit 32 and consequently does not move with the intermediate conduit.

In operation, the coal falls from the bunker 16, through an opening 17 in the tender deck, into the trough 26. The conveyor screw 18 transfers the coal through the trough 26. The inclined screw 23 conveys the coal from the trough 26 forward and upward above the level of the cab deck, and is the only means for moving the coal through the intermediate conduit 22 and the backhead conduit 32 to the distributor plate 33. The distributor plate 33 is secured to the backhead conduit 32 in any suitable manner and extends

forwardly into the firebox. Immediately at the rear of the distributor plate 33 are the nozzles 34 which issue fluid jets for discharging the fuel over the firebed. The nozzles 34 are in communication with cored passages 35 and pipe lines 36 are in communication with the cored passages

35. The pipe lines 36 lead to a source of pressure

105
 110

fluid (not shown) and have suitable valves (not shown) for varying the pressure of the fluid jets.

What I claim as new is:—

In a locomotive having a firebox, a cab, a cab deck and a backhead provided with a firing opening, a tender for said locomotive, a tender deck, a stoker having a conduit rigidly attached to the backhead in communication with said opening, a conduit horizontally and rigidly mounted as a pre-assembled unit on the tender beneath the tender deck, an intermediate conduit flexibly connected to the two named conduits by ball and socket joints, said intermediate conduit sloping forwardly and upwardly from the forward end 15 of the second named conduit through the cab deck into the cab to the rear end of the first named conduit, a conveyor screw in each of

the second and third named conduits, the screw of the latter conduit extending forwardly into the first named conduit, said screws being universally jointed together and comprising the sole means for transferring fuel through the three conduits in a stream unobstructed by screw shaft hanging bearings, the screw in said intermediate conduit arranged to convey the fuel from below the elevation of the cab deck to a point above the cab deck, the bottom surface of the first named conduit, forward of its ball and socket joint, being inclined and substantially straight along its medial line, a distributor plate extending forward from the first named conduit, and fluid jets issuing from nozzles at the rear of said distributor plate for discharging the fuel into the firebox.
